Primary Examiner — Philip S Hyder*Assistant Examiner* — Darlington Ly(74) *Attorney, Agent, or Firm* — Head, Johnson & Kachigian, P.C.(57) **CLAIM**

The ornamental design for a tool bit driver, as shown and described.

DESCRIPTION

FIG. 1 is an enlarged front elevation view of the tool bit driver; FIG. 2 is an enlarged rear elevation view thereof; FIG. 3 is a right side elevation view thereof, the left side elevation view being a mirror image thereof; FIG. 4 is a top plan view thereof; FIG. 5 is a bottom plan view thereof; and, FIG. 6 is a perspective view thereof.

The broken lines shown in the drawings illustrate portions of the tool bit driver that forms no part of the claimed design.
